Inventor:

Wolfgang Hermann,
Bydgoszcz, Su, Chittagong, Mysore,
A. 1873.

UNITED STATES PATENT OFFICE.

WOLFGANG HERMANN, OF CHICAGO, ILLINOIS, ASSIGNOR TO METAL SPECIALTIES MANUFACTURING COMPANY, OF CHICAGO, ILLINOIS, A CORPORATION OF ILLINOIS.

DASH LAMP.

Application filed September 20, 1924. Serial No. 738,955.

This invention relates particularly to a dash lamp which can be readily mounted on an instrument-plate carried by an automobile-dash.

6 The primary object is to provide an improved dash lamp of this character which can be readily applied, which is thoroughly adapted to its purpose and which can be cheaply manufactured.

10 The invention is illustrated in its preferred embodiment in the accompanying drawings, in which—

Figure 1 represents a broken front elevational view of an automobile-dash upon which is mounted an instrument-plate having applied thereto the improved dash lamp; Fig. 2, a broken rear elevational view of the same; Fig. 3, a vertical sectional view taken as indicated at line 3 of Fig. 1; Fig. 4, a vertical sectional view, on an enlarged scale, taken as indicated at line 4 of Fig. 1; Fig. 5, a broken plan view of the dash lamp bracket; and Fig. 6, a rear elevational view of the dash lamp device.

25 In the illustration given, A represents a sheet metal dash of an automobile; B, an instrument-plate removably mounted thereon, which carries a switch device B' and an ammeter B²; and C, the improved dash lamp mounted on the instrument-plate.

The dash A and instrument-plate B are of well-known construction. The dash is provided centrally with a large opening, or slot, 1, whose upper wall is designated 1^a.

35 The instrument-plate B is detachably secured to the dash by screws 2, and forms a covering for the opening 1.

The instrument-plate B is provided peripherally with a rearwardly turned flange 3 which bears against the front surface of the dash A.

The dash lamp C comprises a plate-clamping bracket C' and an electric connector C² mounted thereon.

45 The bracket C' comprises a cup-shaped base 4 which bears against the front surface of the upper portion of the instrument-plate B, and a clamping arm 4^a which preferably is formed integrally with the upper portion of the base member 4. The bracket preferably is formed from sheet metal having one portion cupped to form the base 4 and having a web 4^b which is adapted to extend over the upper flange of the instru-

ment-plate B. The arm 4^a has a relatively 55 broad portion 4^c, from which depends the central clamping tongue 4^d which has its lower extremity bent forwardly to form an inclined flange 4^e which engages the rear surface of the instrument-plate B, preferably slightly below the base 4. Flanking the upper portion of the tongue 4^d are rearwardly turned lugs 4^f which engage the upper wall 1^a of the slot 1.

In forming the bracket, the arm 4^a is 65 bent sufficiently toward the base 4 to cause the device to clamp the instrument-plate B when it is applied thereto.

The arm 4^a is provided with a large central perforation 5, and the web portion 4^b 70 of the bracket is provided with a slot 6 which intercepts the opening 5. Thus, there is provided a channel for the passage of the electric conductor 6^a.

The electric connector C² is shown as comprising a sleeve 7 in which is mounted a longitudinally movable insulation plug 8, equipped with a central contact 9 which is in electrical connection with the conductor 6^a. The outer end of the sleeve 7 is provided with a socket 7^a for the lamp bulb 10. This socket may have the usual bayonet slots for connection with the lamp bulb, or threaded connection may be employed, if desired.

Upon the front end of the sleeve 7 is mounted the usual hood-reflector, 11. In the illustration given, a spring 12 is interposed between the movable plug 8 and the base of the lamp. The plug may be shifted longitudinally in the sleeve 7 to make and break the contact by means of a handle, or pin, 13, which works in a suitable cam slot 13^a with which the sleeve 7 is provided.

The sleeve 7 preferably is provided near 95 its inner end with a flange, or bead, 7^b, and the inner extremity of the sleeve extends through a perforation in the base 4 and is spun outwardly to provide a retaining flange 7^c. Thus, the sleeve 7 is securely fastened to the hollow base portion 4 of the bracket.

The central contact 9 of the plug 8 preferably is a spring projected contact mounted in a bushing 9^a whose rear end is fitted with 105 a plug 9^b having a bore for receiving the wire of the conductor 6^a. The wire is secured in the bore by means of a screw 14.

The web portion 6^b of the bracket C' preferably has the metal struck outwardly to provide reinforcing ribs 15.

It will be understood that the instrument-plate B may be removed from the dash, and that the dash lamp may be applied to the instrument-plate by slipping it over the upper edge of the central portion of the plate, the spring arm yielding to permit this action. When the plate is reapplied to the dash, the lugs 1^a are caused to engage the upper wall of the opening in the dash. Thus, the bracket of the dash lamp clampingly engages the upper portion of the instrument-plate and has its clamping arm clamped between the instrument-plate and the dash.

The foregoing detailed description has been given for clearness of understanding only, and no unnecessary limitations should be understood therefrom, but the appended claims should be construed as broadly as permissible in view of the prior art.

What I regard as new, and desire to secure by Letters Patent, is:

1. A dash lamp device comprising an electric connector, and a supporting bracket adapted to clamp on an instrument plate comprising a base adapted to bear on the front surface of the plate and upon which said connector is mounted, and a spring arm connected with the upper portion of said base and having an extremity adapted to bear against the rear surface of the instrument plate, said arm having a rearwardly extending lug adapted to engage the upper wall of a slot in the dash.
2. A dash lamp device comprising an electric connector, and a sheet-metal bracket having a hollow base portion adapted to bear against the front surface of an instrument-plate and carrying said connector and having a web adapted to extend over the upper edge of an instrument-plate and an arm adapted to depend back of the plate,

said arm being equipped at a point distant from the web with a rearwardly extending lug, for the purpose set forth.

3. In combination, a metal dash provided with an opening, an instrument-plate removably secured to said dash, and a dash lamp device comprising an electric connector and a bracket supporting said connector, said bracket having a base portion upon which the connector is mounted and which bears against the front surface of the upper portion of the instrument-plate and said bracket having also a clamping arm interposed between the upper portion of the instrument-plate and the dash.

4. In combination, a metal dash provided with an opening, an instrument-plate detachably secured to said dash and covering said opening, and a dash lamp device comprising an electric connector and a supporting bracket, said bracket having a base portion upon which the connector is mounted and which bears against the front surface of the upper portion of the instrument-plate and said bracket having a web portion extending over the upper edge of the instrument-plate and an arm depending from said web portion, said arm having a portion engaging the rear surface of the instrument-plate and having a portion engaging the wall of the opening of said dash.

5. A dash lamp device comprising an electric connector, and a supporting bracket adapted to clamp on an instrument plate and embrace the upper portion only of said plate and comprising a base adapted to bear on the upper portion of the front surface of the plate and upon which said connector is mounted, and a spring arm connected with the upper portion of said base and having an extremity adapted to bear against the rear surface of the instrument plate at a point distant from the upper edge of the plate.

WOLFGANG HERMANN.
